(57) **CLAIM**

The ornamental design for a power device package, as shown and described.

DESCRIPTION

FIG. 1 is a top perspective view of a power device package showing my new design;

FIG. 2 is another top perspective view thereof;

FIG. 3 is a bottom perspective view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a back elevation view thereof; and,

FIG. 9 is a front elevation view thereof.

The broken lines shown in the drawings represent portions of the power device package that form no part of the claimed design.
